UNITED STATES PATENT OFFICE.

GEORGE SEMEL, OF NEW YORK, N. Y.

DESIGN FOR A BEDSTEAD.

SPECIFICATION forming part of Design No. 26,415, dated December 15, 1896.

Application filed October 20, 1896. Serial No. 609,469. Term of patent 3½ years.

To all whom it may concern:

Be it known that I, GEORGE SEMEL, a citizen of the United States, residing at New York, in the county of New York and State of New York, have invented and produced a new and original Design for Bedsteads; and I do declare the following to be a full, clear, and exact description of the same, reference being had to the accompanying drawing, forming a part thereof.

The figure is a perspective view of a bedstead, showing my design.

The leading feature of my design consists in the corrugated vertical tubes when used with or without ornaments and in connection with the other parts which collectively form the head-board or foot-board of a bedstead.

1 1 are the usual supports or pillars employed in metallic bedsteads; 2 2, parallel vertical tubes connecting said parts; 3, vertical tubes arranged parallel between the tubes 2 2 and corrugated or formed as a waved line over a portion of their length, as shown at 4. I may carry the corrugations or waved

line through the whole length of the vertical tubes. 25

5 represents ornaments at the connection between the transverse tubes 2 and the vertical tubes 3. Similar ornaments 6 are located on the vertical tubes 3. 30

7 represents curved tubes which are connected through an ornament 8.

9 are spheres on the ends of the pillars 1.

I wish it understood that the general shape or design of the pillars 1, transverse tube 2, 35 curved tubes 7, and the ornaments 5 and 8 employed may be varied without in any wise affecting the essential feature of my design.

What I claim is—

The design for a bedstead substantially as 40 herein shown and described.

In testimony whereof I affix my signature in presence of witnesses.

GEO. SEMEL.
